(57) **CLAIM**

The ornamental design for a "magazine for data cartridges", as shown and described.

DESCRIPTION

FIG. 1 is a perspective view of a magazine for data cartridges;

FIG. 2 is a top view thereof;

FIG. 3 is a front view thereof;

FIG. 4 is a bottom view thereof;

FIG. 5 is a left side view thereof, the right side is a mirror image thereof except for the small diagonal contour line on the top narrow element;

FIG. 6 is a rear view thereof; and,

FIG. 7 is a rear perspective view thereof.
